CLAIM

The ornamental design for a housing for a reverse osmosis water purification unit, substantially as shown and described.

DESCRIPTION

FIG. 1 is a perspective view of a housing for a reverse osmosis water purification unit showing my new design; FIG. 2 is a front elevational view thereof, the rear view being identical thereto; FIG. 3 is a top plan view thereof; FIG. 4 is a bottom plan view thereof; FIG. 5 is a left side elevational view thereof; and FIG. 6 is a right side elevational view thereof.

FIG. 1

FIG. 3

FIG. 2

FIG. 4

FIG. 6

FIG. 5
